TELEVISION ANTENNA

Harold F. Rieth, Los Angeles, Calif., assignor to Packard Bell Electronics Corporation, Los Angeles, Calif., a corporation of California

Filed May 2, 1960, Ser. No. 60,419

Term of patent 14 years

(Cl. D26—14)

Figure 1 is a front perspective view of a television antenna with the arms in extended position, showing my new design;

Figure 2 is a rear elevational view with the arms in extended position, the front being substantially a mirror image thereof;

Figure 3 is a side elevational view with the arms in extended position, the opposite side being substantially a mirror image thereof;

Figure 4 is a side elevational view in a telescoped position, the opposite side being substantially a mirror image thereof; and

Figure 5 is a fragmentary side elevational view, to an enlarged scale, showing the end of one of the arms.

The twin-lead shown in broken lines is for illustrative purposes only.

I claim:

The ornamental design for a television antenna, substantially as shown and described.
